United States Patent Office.

DUNCAN FORBES, OF CHICAGO, ILLINOIS.

Letters Patent No. 83,949, dated November 10, 1868.

IMPROVED FOLDING LOUNGE.

The Schedule referred to in these Letters Patent and making part of the same.

To all whom this may concern:

Be it known that I, DUNCAN FORBES, of Chicago, in the county of Cook, and State of Illinois, have invented an Improved Folding Lounge; and I do hereby declare that the following is a full, clear, and exact description of the construction of the same, reference being had to the accompanying drawings, and letters marked thereon, making a part of this description, in which—

Figure 1 is a perspective representation of my invention, as when closed and used as a lounge.

Figure 2, a perspective representation of the same, as when unfolded and used as a bed.

Figure 3, a longitudinal section of the folding part.

Figure 4, a transverse section of the lounge.

Figure 5, an elevation of one of the frames of the folding bolster.

The present invention consists in a novel combination of a two-part bolster with a peculiarly-arranged spring-top, the whole being an improvement on the ordinary folding lounge.

To enable others skilled in the art to fully comprehend the construction of my invention, I have marked corresponding parts with similar letters, and will now give a detailed description.

A T H represent the body of the folding lounge, which is constructed similarly to those now in common use, and therefore it needs no particular description.

The folding part A is hinged to that part of the body shown at H, at n, fig. 4, drawing 2, and it is made to open or shut, as seen at figs. 1 and 2, drawing 1.

This folding part, A, is made with a frame, S N M, figs. 3 and 4, drawing 2, and the ends of the frame N M are made to support the ends of two or more slats, K K, running lengthwise with the lounge, and being put between the coils of the springs L L. This ar-

angement of the springs and slats is necessary, as the former are made to give elasticity to both sides of the folding part A. And if this or a similar device is not used, the upholstery is very liable to stretch and sag, unless unusual care is taken to secure the spring with canvas; and then a greater number of springs must be used to obtain the necessary support.

A folding bolster, D D, is hinged to the foot of the lounge, as shown at fig. 2, drawing 1, and figs. 3 and 4, drawing 2, and it is made to have, when open, a suitable inclination for supporting the head of the occupant, by means of an incline, J, at the top of that part of the frame shown at M. And this bolster is made with two metal frames, shown at fig. 5, drawing 2, covered with canvas, or some strong fabric, the middle F, fig. 2, drawing 1, of which permitting the bolster to fold together, as shown at fig. 4, drawing 2, when the part A is closed. This bolster can be made of other material than that described, but I prefer the iron frames, in view of strength, and the little room they occupy between the mattresses when the lounge is closed.

An ordinary drawer, B, fig. 1, is made to slide under the lounge, and it is supported by cleats fastened to the inside of the legs W, or otherwise, as desired, and it will be found very useful and convenient for holding bed-clothes, wearing-apparel, &c.

Having thus described my invention, I do not claim a folding lounge; but

What I do claim, and desire to secure by Letters Patent of the United States, is—

The combination of the two-part bolster D D, body H, and folding part A, the whole being arranged substantially as and for the purpose set forth.
